DESIGN FOR A COMBINED DRAIN BOARD AND DRIER COVER

Fred A. Conterman, Jamestown, N. Y., assignor to Blackstone Manufacturing Company, Inc.,
Jamestown, N. Y., a corporation of New York

Application February 7, 1939, Serial No. 82,848

Term of patent 7 years

To all whom it may concern:

Be it known that I, Fred A. Conterman, a citizen of the United States, residing at Jamestown, in the county of Chautauqua and State of New York, have invented a new, original, and ornamental Design for a Combined Drain Board and Drier Cover, of which the following is a specification, reference being had to the accompanying drawing, forming part thereof, and in which the figure is a perspective view of a combined drain board and drier cover showing my new design.

I claim:

The ornamental design for a combined drain board and drier cover, substantially as shown.

FRED A. CONTERMAN.
